UNITED STATES PATENT OFFICE.

CHARLES D. GOODWIN, OF NEW HAVEN, CONNECTICUT.

DESIGN FOR A TOY.

SPECIFICATION forming part of Design No. 17,200, dated March 22, 1887.

Application filed October 6, 1886. Serial No. 215,512. Term of patent 15 years.

To all whom it may concern:

Be it known that I, CHARLES D. GOODWIN, a citizen of the United States, residing at New Haven, in the county of New Haven and State of Connecticut, have invented and produced a new and original Design for a Toy, of which the following is a specification, reference being had to the accompanying photograph, forming part thereof.

10 The photographic illustration shows in detail the ornamentation and arrangement of this design, which consists in a group of figures in Japanese costumes, with certain heads

and arms of said figures represented as detached from their trunks, the whole disposed upon a background of Japanese scenery.

I claim--

The design for a toy herein shown and described, the same consisting in the figures in Japanese costumes, with the heads and arms represented as detached from their trunks, and the background of Japanese scenery.

CHARLES D. GOODWIN.
